Primary Examiner — Cathron Brooks*Assistant Examiner* — Sharon S Oum(74) *Attorney, Agent, or Firm* — Polsinelli PC; Adam C. Rehm**CLAIM**

The ornamental design for a display screen or portion thereof with graphical user interface, as shown and described.

DESCRIPTION

FIG. 1 is a front view of a display screen or portion thereof with graphical user interface showing the new design; FIG. 2 is a front view of a display screen or portion thereof with graphical user interface showing an alternate embodiment;

FIG. 3 is a front view of a display screen or portion thereof with graphical user interface showing an alternate embodiment;

FIG. 4 is a front view of a display screen or portion thereof with graphical user interface showing an alternate embodiment;

FIG. 5 is a front view of a display screen or portion thereof with graphical user interface showing an alternate embodiment;

FIG. 6 is a front view of a display screen or portion thereof with graphical user interface showing an alternate embodiment;

FIG. 7 is a front view of a display screen or portion thereof with graphical user interface showing an alternate embodiment; and,

FIG. 8 is a front view of a display screen or portion thereof with graphical user interface showing an alternate embodiment.

The outermost broken line illustrates a display screen or portion thereof and forms no part of the claimed design. The remaining broken lines, showing portions of the graphical user interface, form no part of the claimed design.
